Nov. 19, 2002 (WO) DMA/005 933

(57) **CLAIM**

(51) LOC (7) Cl. **07-05**

The ornamental design for a boiler housing generating steam
for steam irons, as shown.

(52) U.S. Cl. **D32/73**

DESCRIPTION

(58) **Field of Search** D32/68-71, 73;

FIG. 1 is a perspective view showing my design;

38/75, 77.1, 77.83, 77.9, 79, 142; 219/245,

FIG. 2 is a front elevational view thereof;

247, 259; 248/117.1, 117.2, 117.3; 392/324,

FIG. 3 is a rear elevational view thereof;

333, 394, 399, 403-405

FIG. 4 is a left side elevational view thereof;

(56) **References Cited**

FIG. 5 is a right side elevational view thereof;

U.S. PATENT DOCUMENTS

FIG. 6 is a top plan view thereof; and,

2,595,243 A * 5/1952 Gordon 219/247
D388,921 S * 1/1998 Doria D32/73

FIG. 7 is a bottom plan view thereof.
